2 SHEETS—SHEET 2.

UNITED STATES PATENT OFFICE.

OTTO H. FEUCHT, OF ST. LOUIS, MISSOURI.

GRINDER.

1,418,433.

Specification of Letters Patent. Patented June 6, 1922.

Application filed October 27, 1921. Serial No. 510,945.

To all whom it may concern:

Be it known that OTTO H. FEUCHT, a citizen of the United States of America, residing at 1312^a Sullivan Avenue, in the city 5 of St. Louis and State of Missouri, has invented certain new and useful Improvements in Grinders, of which the following is a specification.

The object of my invention is to manufacture a cylinder grinder which will be simple in construction, capable of being easily and simply manufactured at small cost and which can be adjusted to cylinders of varying sizes. A further object is to 10 devise a cylinder grinder in which the spindle will have a planetary as well as a rotary motion and one in which the eccentricity of the spindle can be accurately but simply adjusted.

With these and other objects in view my invention has relation to certain novel feature of construction and arrangements of parts as will be hereinafter more fully described, pointed out in the claims, and 15 illustrated in the drawings in which

Fig. 1 is a front elevation of my device with the supporting members removed and in which—

Fig. 2 is a plan view of my device and 20 in which

Fig. 3 is a longitudinal sectional elevation of my device and in which

Fig. 4 is a cross section taken along the line 4—4 of Fig. 3 and in which

Fig. 5 is an end elevation of my device with the spindle and its appurtenances removed.

Numeral 6 designates a spindle having a shoulder 7 and a reduced portion 8 with 40 threads 9 near its one extremity and a further reduced portion 10 at the same extremity. Numeral 11 indicates a grinding stone of conventional type and character which is secured to the end of the spindle 6 by means of the screw 12. A washer 13 is interposed between the head of the screw 12 and the stone 11. The inner face of the stone 11 rests partially on the shoulder 14 of the spindle 6.

Mounted on and partially enveloping the spindle 6 is the tube 15 made in two parts which is of such length that when in position on the reduced portion 8 of the spindle 6 that its one end rests flush against the

shoulder 7 and that its other end partially 55 envelopes the threads 9. In order to secure the spindle 6 in the tube 15 the lock washers 16 and 17 are screwed on to the threads 9. The tube 15 has secured thereto exteriorly a rectangular casting 18 which holds the 60 two portions of the tube 15 together and which has parallel sides 19 and 20, which sides are not parallel to the axis of the spindle 6 but which are located at a perceptible angle with the axis of the spindle 6. 65 The rectangular casting 18 forms shoulders with the spindle 6 at 21, 22, 23 and 24 as best shown in Fig. 3. Numeral 25 designates a wedge of a cross section best shown in Fig. 4 and of a longitudinal section best shown 70 in Fig. 3. Numeral 26 designates a similar wedge likewise shown best in the same figures. These wedges 25 and 26 are positioned on the rectangular casting 18 on the spindle 6 with the smaller end of the wedge 75 26 at the right as shown in Fig. 3. Secured at its center to the wedge 25 is the fragmental segmental annular section 27 having the external threads 28. Oppositely disposed and similarly formed is the fragmental annular segmental section 29, having the external threads 30. Numeral 31 designates 80 a hollow internally threaded wheel having the worm threads 32 on its periphery. The internal threads of the wheel 31 are in engagement with the threads 28 and 30 of the fragmental annular segments 28 and 29. Numerals 33 and 34 designate segments of 85 cylinders which are secured in the wheel 31 as best shown in Fig. 4 to the rectangular 90 casting 18 of the spindle 6 and partially cover the wedges 25 and 26 and in sliding engagement with the wedges. The detachable securing means of these cylinder segments are projections on the rectangular 95 casting 18 and apertures on the inner surfaces of the cylinder segments. Numeral 35 designates an annular sleeve which is positioned over the spindle 6, the rectangular casting 18, the wedges 25 and 26, and the 100 cylinder segments 33 and 34 and in direct contact with the latter. Numeral 36 designates a pulley formed in the periphery of the sleeve 35 which pulley projects beyond the cylinder segments 33 and 34, the wedges 105 25 and 26, and the rectangular casting 18. Numeral 37 designates a sleeve substantially similar to the sleeve 35 and positioned over

the same elements on the right in Fig. 3 as the sleeve 35 is positioned on the left in the same figure. The sleeve 35 at its left end in Fig. 3 is screwed to the cylinder segments 33 and 34 by the screws 38 as best shown in Fig. 5. The sleeve 37 is likewise screwed to the segments 33 and 34 at their right end as best shown in Fig. 3. The outer surfaces of the sleeves 35 and 37 act as journals 10 and are positioned in the journal boxes 39 and 40, the wheel 31 being sustained between them. The boxes 39 and 40 are screwed to the frame 41. At the left end of the spindle 6 is detachably secured the pulley 15 42. It will be seen that by a rotation of the pulley 42 that the spindle 6 will be rotated and that by a rotation of the wheel 31 that the wedges 25 and 26 will be moved longitudinally in opposite directions and 20 that therefore, the spindle 6 will be moved eccentrically and that therefore, the stone 11 will be likewise moved eccentrically. Numeral 43 designates a bifurcated hook having its prongs bent fragmentally circumferentially as best shown in Fig. 4 and being joined by the U portion 44 in which is formed the hole 45. Numeral 46 designates a similar hook. In the prongs of the hooks are formed holes 47 through which screws 30 48 pass into holes formed in the cylinder segments 25 and 26; both of the hooks being similarly fastened on opposite sides. Numeral 49 designates a worm which is in mesh with the external teeth of the wheel 35 31 and which is mounted on the shaft 50 which shaft passes through the holes 45 in the U portions of the hooks 44 and 46, the worm being positioned between the hooks. Numeral 51 designates a head secured to 40 the shaft 50. It will be seen that by turning the head 51 that the shaft 50 and hence the worm 49 and hence the wheel 31 will be rotated and that by means of such rotation the eccentricity of the spindle 6 may be 45 altered.

Numeral 52 designates a conventional lathe stand or table on which the device thus far described is mounted with the spindle 6 in substantially a horizontal plane. Numeral 53 designates the top of the stand 52. Numeral 54 designates a movable block for holding the cylinder that is to be ground. This block is of conventional type, the cylinder being secured between the horizontal 55 members 55 which are relatively adjustable by virtue of the screw 56. The block 54 is mounted on a conventional track such as is used on lathes for moving the block horizontally on the stand 52. The cylinder is positioned in the block at such height that when the block is moved toward the spindle 6, the stone 11 will be moved to the interior of the cylinder. In order to move the block 54 horizontally the conventional wheels 57 and 65 58 are provided in the table 52. Over these

wheels and screwed to the block 54 is passed the chain 59 which chain is in mesh with teeth on the wheels 57 and 58. By a rotation therefore, of the wheel 57 the block 54 will be moved longitudinally. Numeral 60 indicates a handle on the wheel 57 to facilitate rotation of the wheel 57.

The pulley 35, which offers means for applying the power for the rotation of the wheel 31 and the parts thereto attached, is 75 so positioned relative a shaft and wheel attached to the table 52 that a belt may be passed from the pulley 35 to such a wheel or pulley 61 which pulley is mounted on a shaft having a conventional clutch 62. I have 80 not made a more specific disclosure of the clutch 62 and of the clutch 63 because they will be readily understood from the drawing and the remainder of this description. The clutch 63 is used to engage and disengage 85 the power from the pulley 42 and the clutch 62 to engage or disengage the power from the pulley 35.

It will be seen that the rotation of the pulley 35 produces the planetary motion and 90 that the rotation of the pulley 42 produces the rotary motion. By means of the wheel 51 the eccentricity of the stone 11 may be delicately adjusted. The rotary motion is a great deal faster than the planetary motion, that is to say that if the rotary motion made 3,500 revolutions a minute that the planetary motion would make 60 revolutions a minute.

In the operation of my device after the 100 cylinder is properly positioned it is moved longitudinally from left to right in Fig. 1 presenting the stone 11 to each point of the cylinder for the entire length of the cylinder.

What I claim and mean to secure by Letters Patent is—

1. In combination with a spindle on one end of which is positioned a stone, a rectangular casting secured to said spindle, wedges in sliding engagement with said rectangular casting and means of moving said wedges longitudinally relative said rectangular casting.

2. In combination with a spindle at one end of which is secured a stone, a rectangular casting secured to said spindle, wedges in sliding engagement with said casting, cylinder segments in sliding engagement with said wedges, internally threaded segmental annular sections secured to said cylinder segments, an internally threaded wheel in threaded engagement with said segmental annular sections, a worm in threaded engagement with said wheel, and means for 115 rotating said spindle.

3. In combination with a spindle having a stone secured at its one end, a rectangular casting secured thereto, wedges in sliding engagement with said casting, cylinder seg- 130

ments in engagement with said wedges, said cylinder segments having secured thereto fragmental segmental annular sections, an internally threaded wheel, said wheel in 5 threaded engagement with said segmental annular sections, a worm in threaded engagement with said wheel, sleeves holding said

spindle, wedges and cylinder segments in operative relationship, and means of imparting rotary motion to one of said sleeves and 10 independent rotary motion to said spindle.

In testimony whereof I affix my signature.

OTTO H. FEUCHT.
